UNITED STATES PATENT OFFICE.

TRUMAN S. HASTINGS, OF DETROIT, MICHIGAN.

ELECTRICAL SIGN.

1,118,765.

Specification of Letters Patent. Patented Nov. 24, 1914.

Application filed May 29, 1913. Serial No. 770,557.

To all whom it may concern:

Be it known that I, TRUMAN S. HASTINGS, a citizen of the United States, residing at Detroit, in the county of Wayne and State of Michigan, have invented new and useful Improvements in Electrical Signs, of which the following is a specification.

This invention relates to electric signs having changeable illuminated letters, particularly that type in which a field of light units is provided, to be energized in any desired order at will, and adapted to be used to represent line drawings of script in process of formation. I am familiar with such construction for this purpose as illustrated in the Patent No. 1,040,475, and the one numbered 546,799, and it is an object to give a construction and method whereby the practicability of such a display will be further increased.

An important object is to enable the very close spacing of the contact units on a master board from which the display field may be controlled by means of a pencil brush 25 manipulated in the same way that an ordinary drawing lead pencil would be.

It is a further important purpose to enable the control of a light circuit by an electro-magnetic circuit maker and breaker, in such a way that liability of heating of a small magnet by a sustained current required for its operation is obviated.

An important attainment of the invention is the facilitation of a correction, which may be made with certainty without the necessity for cutting out any but the particular lights improperly lit, the operating pencil being applicable to use as the correcting agent without the manipulation of any switches or 40 cutouts.

Additional objects and advantages will appear, some being apparent from the following description and from the drawings, in which—

Figure 1 is a diagrammatic view of the lighting circuits, Fig. 2 is a similar view of the actuating circuits for the circuit breakers, Fig. 3 is a detail of the switch in the lighting circuit at the circuit breakers.

There is illustrated diagrammatically a section of a sign 10 comprising a multiplicity of lamp units 11 arranged in orderly series very closely spaced together, the construction of which may be readily understood by those versed in the art, so that the actual

mechanical construction of the sign and the mounting for the lights, etc., is not illustrated. Equal numbers of the lights are connected at one side with the positive and negative leads 12 and 13 of the generators 14 and 15, the negative and positive leads 16 and 17 are connected to the neutral 18 of the usual three wire circuit. In a suitable situation, a corresponding series of switch units 19 are mounted, including each a switch 20 one terminal of each switch being connected to the neutral, while the other is connected by one of the branch wires 21 to a respective lamp 11, at the side opposite that on which the lamp is connected with the generator lead 16 or 17 as the case may be. Thus when the switch is closed, the particular lamp to which it is connected is energized.

A master board 22 is provided, having contacts each connected by a direct actuating wire 23 to one end of the winding of the magnet 24 of the unit 19 arranged to energize a lamp 11 corresponding in position on the board or field of the sign 10 with the position of the particular contact on the master board. The details of the mechanical construction of the board not being a part of this invention are not illustrated, and will be understood readily by those versed in the art. It is desirable, however that the board 25 have a perfectly smooth face, and that the contacts be set flush therein and also smoothly finished, so that the brush pencil may slip easily thereon. It is also considered desirable that the board and contacts be made of dark material, and the surface of the board and contacts covered before each operation of the device with a coating of chalk, or some other light colored material suitable for the purpose, whereby when the pencil is moved 30 over the face of the board, visible lines will be made forming a record of what is on the sign.

The construction of the pencil is very simple, and comprises merely a cylinder 26 of some non-conducting material provided at respective ends with contact portions 27-27 of suitable form, the first named being connected with the negative terminal of a battery 28 and the other being connected 35 to the positive terminal of the battery by wires 29 leading from the side of the pencil near the middle, as indicated. These contacts may be of any desired form, for the purposes in view and may consist of a small 40

bunch of wires, by which broad lines may be produced in the letters represented, by slight pressure, or any other suitable device may be employed as a brush contact. The 5 contact 27 is utilized to illuminate the sign.

The circuit making and breaking units each comprise an electromagnet 24 mounted upon a suitable insulator support 30, upon which is resiliently mounted the armature bar 10 31 normally spaced from, but arranged to move toward the magnet when energized. The positive electrode of the battery is connected by wire 24' directly with one end of the winding of the magnet opposite its connection with the master board 22. The armature is connected with the negative terminal of the battery direct by a wire 31' and on the support 30 there is a resistance and contact 32 arranged to be engaged by a screw 20 33 in the armature when the armature is actuated by the magnet. This contact and resistance 32 is connected by wire 32' with the same end of the magnet winding as the respective contact of the master board. Thus 25 when the contact 27 is engaged with a contact in the master board a circuit is completed through a magnet, which, drawing the armature down will complete an independent circuit directly to the battery 30 through the contact resistance 32, the armature, and wire 31', so that the magnet will remain energized when the pencil is removed from the respective contact on the board 22. The armature is provided with an arm 34 35 projecting some distance beyond the magnet oppositely from the pivot of the armature, so that it has considerable movement at its extremity under effect of the magnet, and carried thereby in a suitable manner there is 40 a switch yoke 35, having two arms arranged to move into respective cups 36 of a mercury switch 20, the cups being formed in a block 37 of suitable material. The cups are partly filled with mercury 38, and on the mercury 45 there is a body of oil 39, sufficient to fill the cups when the arms of the yoke are fully engaged therein. The depth of the oil exceeds that of the mercury, as shown, but this 50 proportion is not arbitrary. By having the mercury at the same level in each cup and the arms of the yoke arranged to engage the mercury simultaneously, sparking is practically eliminated, and a good contact effected without friction, so that a very small magnet 55 is ample for its operation.

It will be seen that a very small amount of current will be required to operate the devices, so that there need be no danger of overheating of the magnets no matter how long they are energized, and the lighting circuit will have no effect on the controlling circuit. It will be appreciated that with a low voltage current, as well as one with a 60 very low amperage, which may be used to control the light circuits, the contacts on

the master board may be very closely spaced, without objectionable sparking or possibility of dangerous shock in using the pencil, and the liability of accidental operation of lights connected with contacts on 70 the board 22 beyond the path of the pencil is also eliminated. In order to quickly clear or darken the entire sign, putting out any lights that may be lit thereon, a simple switch 40 is provided in the direct circuit 75 from the battery to the magnets, the opening of which releases all armatures and opens all switches 20. The low voltage here involved makes sparking practically *nil* and the lights of the sign having individual 80 switches 20, they will all be cut out without sparking and without requiring power or attention.

In the event that an error is made in the writing of a display it will appear on the 85 master board, and by inverting the pencil 26 and rubbing the contact 27 over those on the board 22 in the area of the inadvertent lines, a short circuit is made in the respective energizing circuits outside the magnets, causing the release of their armatures and breaking of the particular lamp circuits, and leaving all other lights undisturbed. This is of great advantage, and the positiveness with which the correction 95 may be made, as well as the obviation of the necessity for putting out all lights and beginning the display all over, will greatly increase the desirability of this method of displaying advertisements.

If it is desired to use very small lamps so that the breadth of the lines drawn will be represented by, say, three lights, the pencil may be provided with a brush formed of a bunch of wires 41 engaged in the end, as shown in Fig. 5.

What is claimed is:

1. A device of the character described comprising a multiplicity of high potential lamp circuits, individual circuit breakers therein, respective resilient means tending to hold the breakers in open position, a corresponding number of electric magnets, armatures connected to respective circuit breakers for closing, and movable by the magnets when energized to close the breakers, a source of low potential current, a direct connection between one pole thereof and one terminal of each of the magnets, a masterboard having contacts thereon each electrically connected with the other terminal of respective magnets, a normally open by circuit from the last named terminal of the magnets to the pole of the said source of opposite potential from the first mentioned, means operable under closing movement of the armature to close the by circuit, a brush member connected to the last named pole for engagement with the contacts to initially energize the magnets, 130

and a similar brush member connected with the first named pole for short circuiting the by circuits individually, as described.

2. In a device of the class described a multiplicity of lamp circuits, electromagnetic circuit makers and breakers for, and tending to break the circuits individually, separate circuits for energizing the breakers comprising a normally open circuit including a contact, a pencil, a brush at one end thereof for closing the circuit as described, a by circuit adapted to be closed by operation of the breakers to close the lamp circuits and a brush at the opposite end of said pencil of opposite potential from the first for engagement with said contact to short circuit the by circuit.

3. A system of electrical distribution including a high potential circuit, a switch for breaking the circuit comprising an in-

sulated body of mercury, a vertically movable switch member, electrical connections with the switch whereby to close the circuit through the mercury and switch member when coengaged, an oscillable arm engaged at its swinging end with the switch member means to open the switch, an armature on the arm, an electromagnet in operative relation therewith, manually operable means to energize the magnet, means operable under closing of the switch to energize the magnet, and means to short circuit said last named energizing means.

In testimony whereof I have hereunto set my hand in presence of two subscribing witnesses.
